US00D765181S

(12) United States Design Patent (10) Patent No.: US D765,181 S
(45) Date of Patent: * Aug. 30, 2016

(54) LABEL

(71) Applicant: Savenia LLC, Bethesda, MD (US)

(72) Inventor: John Jabara, Bethesda, MD (US)

(73) Assignee: Savenia LLC, Bethesda, MD (US)

() Term: 14 Years

(21) Appl. No.: 29/507,856

(22) Filed: Oct. 31, 2014

Related U.S. Application Data

(63) Continuation of application No. 29/472,075, filed on Nov. 8, 2013.

(51) LOC (10) Cl. 19-08

(52) U.S. Cl.

USPC D20/27

OTHER PUBLICATIONS

U.S. Appl. No. 29/472,075, filed Nov. 8, 2013 (unpublished).

* cited by examiner

Primary Examiner — Mary Ann Calabrese

(57) CLAIM

The ornamental design for a label, as shown and described.

DESCRIPTION

The FIGURE is a front view of a label showing my new design.

Thickness of the label forms no part of the claimed design. The top, bottom, left, right and rear views are omitted as they form no part of the claimed design.
